CLAIM

The ornamental design for a mattress cover, as shown and described.

DESCRIPTION

FIG. 1 is a perspective view of a first embodiment of the mattress cover;

FIG. 2 is a first side view of the mattress cover of FIG. 1; FIG. 3 is a second side view of the mattress cover of FIG. 1;

FIG. 4 is a first end view of the mattress cover of FIG. 1; FIG. 5 is a second end view of the mattress cover of FIG. 1; FIG. 6 is a perspective view of a second embodiment of the mattress cover;

FIG. 7 is a first side view of the mattress cover of FIG. 6; FIG. 8 is a second side view of the mattress cover of FIG. 6;

FIG. 9 is a first end view of the mattress cover of FIG. 6; and, FIG. 10 is a second end view of the mattress cover of FIG. 6.

The broken lines shown in the drawings are included for the purpose of illustrating unclaimed portions of the mattress cover and form no part of the claimed design.

1 Claim, 6 Drawing Sheets
